ABSTRACT

A silverware sorting construction for handling knives, forks and spoons. A bed is provided with vibrating means or other devices for moving silverware toward a discharge end of the bed. Knives on the bed are maintained in position and are discharged into collecting means located at the end of the bed. Discharge openings are defined at an intermediate location, and both forks and spoons pass through the discharge openings. A plate is positioned beneath the discharge openings, and slots are defined by the plate for receiving the forks and spoons. The slots are dimensioned so that the forks will pass through the plate into separate collecting means. The spoons are held suspended by their bowls and are moved along the plate to discharge openings at the end of the plate. A separating means may be employed for separating spoons of different size, for example separating spoons with longer handles from spoons with shorter handles. Separate collecting means are then provided for the different types of spoons.

SILVERWARE SORTER

This invention relates to an apparatus for handling silverware. The apparatus is particularly designed for sorting silverware so that knives, spoons and forks can automatically be collected in separate receptacles.

Many institutions, for example schools, restaurants, and industrial cafeterias, handle large volumes of tableware to provide food service. In a typical operation involving cafeteria-style service, plates, saucers, cups, glasses and silverware, as well as cafeteria trays must be collected in some fashion, washed, and then reused.

It is normal practice to manually separate the various items of tableware. The separate stacks of trays, plates, etc., are then manually loaded into dishwashing racks or directed onto conveyors for passage through automatic dishwashing equipment. When the washing operation is completed, additional manual handling of at least some of these items is required to restack the items or to otherwise store them until they are ready for further use.

In copending application Ser. No. 828,510, entitled, "Vibrating Sorter For Soiled Tableware", there is described a system whereby various items of tableware can be conveyed in random fashion for automatic separation of the tableware to thereby minimize manual handling. In copending application Ser. No. 851,927, now U.S. Pat. No. 3,569,752 entitled "Tableware Tray Tilting And Conveying Means", means are described for handling cafeteria trays in a system of the type described in the first mentioned application.

Although the systems described in the previous applications are quite satisfactory from the standpoint of separating various items of tableware, special problems remain insofar as silverware is concerned. Naturally pieces of silverware represent a proportionally higher number of pieces when the total number of pieces used in a particular institution are considered. Accordingly, it is most important to provide means for reducing as much as possible the handling of silverware to thereby minimize labor costs, to save time in the over-all dishwashing operation, and to eliminate handling of clean silverware prior to use in the dining area.

It is a general object of this invention to provide an improved construction for sorting silverware.

It is a more specific object of this invention to provide a silverware sorting construction which operates to automatically separate knives, spoons, and forks so that manual separation of these items can be eliminated.

These and other objects of this invention will appear hereinafter, and for purposes of illustration, but not of limitation, specific embodiments of the invention are shown in the accompanying drawings in which:

FIG. 1 is a plan view of a silverware sorting construction characterized by the features of this invention;

FIG. 2 is a side elevation of the construction;

FIG. 3 is an enlarged front end view of the construction;

FIG. 4 is a cross-sectional view taken about the line 4—4 of FIG. 1;

FIG. 5 is a rear end view of the construction;

FIG. 6 is an enlarged cross-sectional view taken about the line 6—6 of FIG. 1;

FIG. 7 is an enlarged plan view, partly cut away, illustrating the discharge end of the construction;

FIG. 8 is a cross-sectional view taken about the line 8—8 of FIG. 7;

FIG. 9 is an enlarged fragmentary, sectional view taken about the line 9—9 of FIG. 8;

FIG. 10 is a top view of the structure shown in FIG. 9;

FIG. 11 is a plan view of a mechanism employed for separating forks and spoons taken about the line 11—11 of FIG. 14;

FIG. 12 is a vertical, sectional view taken about the line 12—12 of FIG. 8;

FIG. 13 is an enlarged, fragmentary, sectional view taken about the line 13—13 of FIG. 11;

FIG. 14 is a fragmentary, cross-sectional view taken about the line 14—14 of FIG. 11; and,

FIG. 15 is a schematic illustration of the construction with silverware collecting receptacles associated therewith.

The construction of the invention generally includes a bed for supporting knives, forks, and spoons delivered onto the bed. Means are provided for moving the silverware along the bed toward a discharge end. Preferably the system includes 5 vibrating means for this purpose so that the movement can be rather precisely controlled and so that the silverware will move along desired paths, preferably provided by means of troughs defined in the bed.

10 A collecting means for knives includes a chute positioned at the end of the bed. The knives are loaded on the bed, and are retained on the bed until they fall into the chute which guides them to a suitable receptacle.

15 Discharge outlets are provided in the bed ahead of the chute for collecting knives. The forks and spoons all pass through these discharge openings and onto a plate structure defined between the discharge openings. In a preferred form of the invention, this plate structure comprises a lower bed which forms a unit with the upper bed and which is connected to the same vibrating means.

20 Slots are formed in the lower bed, and these slots are dimensioned so that the forks will pass completely through the lower bed into suitable receptacles for the forks. The handles of the spoons will also pass through the slots; however, the slots are not sufficiently large to permit passage of the bowl portions of the spoons. The spoons remain suspended in the slots, and they are moved along the slots, preferably because of the vibrating action.

25 Discharge outlets are provided at the ends of the slots, and the spoons progress through these outlets. In a preferred form

30 of the invention, spoons with longer handles, for example, tablespoons, are separated from spoons with shorter handles such as teaspoons. This separation is accomplished by providing cam means which force the long handled spoons into one side of a separating wall. Means such as an air spray are then employed for forcing the short handled spoons onto the other side of the wall, and separate collecting means are provided for the different types of spoons.

35 The form of the invention shown in the accompanying drawings comprises an upper bed 10 supported on a pan 12. A plurality of delivery conduits 14 are provided for placing silverware of the bed 10. The conduits 14 may be connected to an automatic dishwasher separating apparatus such as described in copending application Ser. No. 828,510. Thus,

40 the construction of this invention may be utilized immediately after silverware has been separated from other types of tableware. After sorting of the silverware in the manner to be described, the silverware may be collected in baskets or other receptacles for passage through a dishwashing machine. If the receptacles are of a suitable type, silverware may be immediately carried in the receptacles for reuse in a restaurant operation or the like. This arrangement will completely eliminate manual handling of the silverware by employees.

45 The system of this invention is also suitable for sorting silverware after the silverware has passed through a dishwashing machine. Thus, the soiled silverware may be loaded in a dishwashing machine in random fashion which is sometimes preferable in order to maintain the individual pieces of silverware in a separated state. After cleaning, the silverware can be 50 delivered to the apparatus of this invention and automatically sorted into individual containers before reuse.

55 The pan 12 is mounted on vertically extending plates 16 which are secured to vibrator 18. The mounting base 21 has springs 22 and 23 at its opposite ends to provide a conventional means for isolating the vibrator assembly. The vibrator is set so that the silverware will progress from the entry end adjacent the conduits 14 toward the opposite end. A plurality of troughs 20 are defined by the bed so that the silverware will move along defined paths. In practice, the silverware is 60 preferably delivered through the individual chutes, one piece at a time, so that there are no pieces on top of each other during travel along the bed 10.

65 Knives typically have handles which allow them to pass over slots 34 without dropping through the slots. Thus, the width, weight, thickness, etc., of the handles causes the knives to

remain in a horizontal position during travel along the bed. The knives, therefore, progress to the discharge end, and are then delivered into a chute 25. This chute defines a narrow end portion 24 which directs all knives out through an opening 26 defined in the end wall 28 of the pan 12.

The knives may be collected by directing the knives down a guide member 55 and into a collecting receptacle 57. Similarly collecting receptacles 59 and 61 may be provided, respectively, for the forks and spoons. Where, as will be described, the spoons are separated by size, a separate receptacle will be located behind the receptacle 61 for receiving spoons directed to the back side of the wall 58. It will be appreciated that a plurality of receptacles will be required depending upon the number of separate discharge positions of the various pieces of silverware. In addition, suitable guide plates may be employed to insure that the respective types of silverware are directed to the proper receptacle.

Because of the curvature of forks and spoons, the handles of these items are positioned at an angle relative to the bottom surface of the troughs 20. As shown in FIG. 8, the handle 30 is at a slight angle relative to the surface 32 of the trough 20. Slots 34 are provided adjacent the end of each trough 20, and these openings are dimensioned so that the handles of the spoons and forks will move into the openings. As indicated, the knives remain in a horizontal position and move past these openings 34.

The attitude of the spoon and fork handles is preferably controlled by providing cam surfaces 36 mid-way along the troughs 20. These cam surfaces tend to locate the handles on edge as shown in FIG. 4 to facilitate movement into the openings 34.

A plurality of short chutes 38 are located beneath openings 34 for delivering the forks and spoons onto the bed 40 of the pan 12. This bed defines a plurality of troughs 42, each defining an elongated slot 44. As best shown in FIGS. 12 through 14, the slots 44 are sufficiently wide to permit forks 46 to fall through the bed 40. Guide elements 48 are provided for directing the forks to suitable receptacles.

The handles of spoons 50 will also pass through the slots 44; however, the bowls of these handles will not pass through whereby the spoons are suspended. Because of the vibrating action, the spoons move along the slots 44 toward discharge openings 52. The spoons then drop through these discharge openings where they are collected by a suitable receptacle.

In most operations involving the handling of silverware, spoons of different types are employed. The spoon 50 is intended to correspond to a teaspoon while the spoon 54 represents a tablespoon or soup spoon. Because of the relative length of the handles of these spoons, means have been developed which will separate the spoons according to size before the spoons drop through the discharge openings 52.

The separating means include a cam 56 positioned beneath each slot 44. This cam is located so that spoons with longer handles engage the cam thereby holding these spoons in a desired position. A wall 58 is located immediately beyond the cam 56 and the cams direct the handles of these longer handled spoons for movement along one side of each wall 58.

The shorter handled spoons are intended to move along the other side of the wall 58. The position of the shorter handled spoons may be controlled by any means located to engage these handles after the longer handles engage the cams 56. For example, air streams may be discharged from one or more openings 62 in nozzles 60 with the air streams engaging each spoon moving along the slots 44. A common air supply 64 is provided for each nozzle. As best shown in FIGS. 13 and 14, the air streams operate to push the shorter handled spoons to one side of the wall 58. The streams also engage the longer handled spoons; however, these spoons are prevented from movement to that side of the wall 58 by the cam 56.

A brush, flexible arm, or other diverting means could be used in place of the air streams. It is preferable that these diverting means be flexible in nature so that the long handles which are in engagement with cams 56 can force their way by

the diverting means. On the other hand, the cams 56 could be designed so that they push the long handles into a significantly different path with other stationary cam means then being employed for diverting the shorter handled spoons.

5 Other means are contemplated for separating spoons or other pieces of silverware depending upon variations in configuration. For example, suitable cams can be designed for engaging the bowls of spoons with bowls of different size being diverted to different collection means.

10 It will be apparent that spoons reaching the discharge openings 52 will fall on opposite sides of the wall 58 depending upon the length of the spoon handles. Suitable collecting means for the different types of spoons are positioned in appropriate places adjacent these walls.

15 The structure described is particularly suitable for use in conjunction with vibrating means. Thus, both of the beds 10 and 40 are connected to the same vibrator and, therefore, all of the desired movement can be accomplished with one power source. It will be appreciated, however, that the bed 40 may be provided by means of a completely independent plate, and separate means may be utilized for moving spoons suspended on this plate. Suitable brush constructions or fluid streams could be employed for imparting movement to the silverware on either bed either as independent power means or in conjunction with the vibrating means.

20 It will be understood that various changes and modifications may be made in the above described construction without departing from the spirit of this invention.

30 That which is claimed is:

1. A construction for sorting silverware including knives, forks and spoons, said construction comprising a bed for supporting silverware, means for moving the silverware along the bed toward a discharge end, the knives on said bed being retained in a substantially horizontal position during movement across the bed, first collecting means positioned adjacent said discharge end for receiving said knives from the bed, at least one discharge opening defined by said bed, said forks and spoons dropping through said discharge opening, a plate positioned beneath said discharge opening, a slot in said plate dimensioned to permit the passage of said forks beyond the plate, second collecting means for receiving said forks, said slot also permitting passage of the spoon handles but being dimensioned to prevent passage of the bowl portion of spoons whereby spoons are suspended by said plate, means for moving suspended spoons along the length of said slot, and third collecting means at the end of said slot for receiving said spoons.

2. A construction in accordance with claim 1 wherein said bed is mounted on vibrating means adapted to move silverware positioned on the bed toward said discharge end.

3. A construction in accordance with claim 2 wherein said plate is attached to said bed whereby said vibrating means also operate to move said spoons along said slot.

4. A construction in accordance with claim 1 wherein said bed defines a plurality of troughs, and wherein said silverware is deposited on said bed and then moves along said troughs toward said discharge end.

5. A construction in accordance with claim 1 wherein said first collecting means for said knives includes a chute having an entry end positioned adjacent the discharge end of said bed and being substantially coextensive therewith, said knives moving along said bed and progressing directly from said bed into said chute.

6. A construction in accordance with claim 1 including means for separating spoons having shorter handles from spoons having longer handles, said separating means comprising a cam element for engaging spoons with a longer handle, and a wall positioned adjacent said cam element, said cam element directing the spoons with long handles on one side of said wall during movement of the spoons along said slot while the spoons with shorter handles move along the other side of said wall.

7. A construction in accordance with claim 6 including air discharge means directed toward the spoon handles during movement of the spoons along said slot, said air discharge means operating to force the spoons with shorter handles to a position for movement of the shorter spoon handles along said other side of said wall.

8. A construction in accordance with claim 7 wherein said third collecting means comprise separate receptacles for receiving spoons having long handles and spoons having short handles.

9. A construction in accordance with claim 6 wherein said plate defines a plurality of separate slots for passage of forks and for suspending spoons.

10. A construction in accordance with claim 1 wherein said forks and spoons are delivered handles-first to said bed, said discharge opening defined by said bed being dimensioned so that said handles bend downwardly into said discharge opening whereby the forks and spoons are directed through the discharge opening.

11. A construction in accordance with claim 10 including a chute positioned beneath said discharge opening operating to direct said forks and spoons handles-first onto said plate.

12. A construction in accordance with claim 1 wherein said plate comprises the bed of a pan structure, said first mentioned bed being mounted on said pan structure above said pan bed, and wherein the means for moving the silverware along said upper bed and along the length of said slot comprises a vibrating means connected to the bottom of said pan structure.

13. A construction in accordance with claim 1 including cam means defined by said bed for locating the handles of said forks and spoons on edge to facilitate dropping of the forks and spoons through said discharge opening.

14. A construction in accordance with claim 1 wherein said bed is maintained in a substantially horizontal position with the silverware being initially placed in a horizontal position on the bed.
